UNITED STATES PATENT OFFICE.

GEORGE W. OLNEY, OF LINCOLN, RHODE ISLAND.

WASHING MACHINE.

Application filed May 13, 1927. Serial No. 191,023.

This invention relates to an improved washing machine and more particularly to an apparatus of this character adapted for use both in the washing of clothes and in extracting the water therefrom.

One object of the invention is to provide a device of this character so constructed as to be capable of use both in washing the clothes and in extracting the water therefrom after washing without removing the clothes from the container.

A further object of the invention is to provide a clothes container capable of use for both washing and rinsing the clothes and so constructed as to reduce to a minimum the liability of injury to the fabrics.

A further object of the invention is to provide an improved clothes container of this character so constructed as to prevent access of the water to the space between the cylinders and thus prevent to a considerable extent the danger of rusting of the metal and consequent injury to the fabrics.

Other objects and advantages of the invention relate to various novel details of construction and improved methods of operation as will be more fully set forth in the detailed description to follow. Referring to the drawings:—

Fig. 1 is a front elevational view of the improved washing machine,

Fig. 2 is a perspective view of the clothes container,

Fig. 3 is a perspective view of one of the bearing blocks inserted within the space between the cylinders at each end of the clothes container, and,

Fig. 4 is a detail sectional view taken along the line 4—4 of Fig. 3.

In the accompanying drawings the numeral 1 designates the casing of the washing machine, which may be of any suitable shape, and to which wash water or rinse water may be supplied or removed therefrom in any suitable manner as will be readily understood by those skilled in the art. The casing 1 is provided at opposite ends thereof with bearings 2 for rotatably supporting a shaft 3, which is adapted to carry the clothes container 4, and which may be driven by a belt and pulley or other suitable drive mechanism after a manner well known in the art. The driving means is preferably so arranged as to permit the rotation of the shaft 3 and clothes container 4 at various speeds and in opposite direc-

tions whereby the apparatus may be readily employed for the washing and rinsing of the clothes as well as for extracting the water therefrom.

The casing 1 is provided with doors 5 hinged thereto as at 6, and provided with handles 7 whereby access may be had to the interior of the casing and to those chambers of the clothes container which are in the uppermost position relative to the shaft 3.

The clothes container 4 comprises a plurality of cylinders 10, each of which has an open end 11, the opposite end thereof being closed. Each cylinder 10 is provided with a plurality of openings 12 formed in the side wall thereof for permitting water to enter or leave the cylinder during rotation of the clothes container. In the preferred form of the invention four cylinders 10 are employed to form the clothes container, although a greater or less number may be used if desired. The cylinders 10 are arranged in parallel relation and are fixedly secured together by rivets or like fastening means 14

passed through those portions of the side walls of the adjacent cylinders which are located in proximity to each other. A layer of rubber or other suitable packing material 15 may be interposed between the meeting sides of adjacent cylinders to prevent water from entering the space between the cylinders. Bands 16 are passed around the cylinders, preferably adjacent to the ends thereof, and secured to the cylinders in any suitable

manner as by rivets or like fastening means 17 for firmly securing the cylinders together. A bearing block 18 is inserted within the space between the cylinders 10 at each end of the clothes container 4, each bearing block 18 being shaped to fit the space between the cylinders and being provided with a central bearing 19 for the shaft 3 and a set screw 21 by which the bearing may be firmly secured to the shaft. The bearing block 18 is provided upon each side with a plurality of openings 23 registering with similar openings in each cylinder wall when the parts are in assembled position, whereby the bearing block 18 may be firmly secured to the cylinders as by rivets or bolts 24. Each bearing block 18 is also provided with an outwardly extending flange 25 formed upon the outer end thereof and overlying the adjacent ends of the cylinders 10, and a packing strip 26 of rubber or other suitable material is preferably inserted between the

flange 25 and the edge of each cylinder to prevent water from penetrating into the space between the cylinders. The bearing block 18 may be provided also with lugs 27 located at opposite corners thereof whereby binding rods 28 may be inserted between each band 16 and the bearing block to firmly bind the parts together and draw the band 16 into tensioning engagement with the cylinders. The bearing block 18 located adjacent to the closed ends of the cylinders is provided with similar lugs 27 for connecting binding rods 28 with the band 16 at the rear ends of the cylinders 10. Only two binding rods 28 may be employed at the front end of the container instead of the four employed at the rear of the container, if desired, or four rods may be used as shown in Fig. 2. Two of the rods at the front of the container may serve as pintles for pivotally mounting oppositely positioned covers 30 opening in opposite directions and each provided with suitable latch means 31 for engaging a projection or lug 32 on the band 16 to retain the covers in position to close the open ends of the cylinders 10.

In the operation of my improved structure the casing 1 may be partially filled with wash water and the clothes to be washed placed in the clothes container by opening the doors 5 and rotating the container 4 into position so that one of the covers 30 will open as shown in Fig. 2 to give access to two cylinders. Clothes to be washed may then be placed in these two upper chambers, the cover 30 for those chambers closed, and the container 4 rotated to bring the two opposite chambers into position in front of the doors 5. The cover 30 for those chambers may then be opened and clothes placed in the chambers. The cover 30 is then closed and latched, and the doors 5 closed, placing the apparatus in condition for use. In washing the clothes the container 4 may be rotated in one direction constantly, or its direction of rotation may be reversed from time to time as desired. If necessary or desirable the treatment of the clothes with wash water may be followed by a similar treatment with rinse water. In both cases it will be seen that in the present construction, the clothes are separated in smaller bulk in each chamber by the provision of a plurality of chambers, and the weight and bulk of the clothes in each chamber thus reduced, whereby the clothes are less liable to injury by reason of their weight, and the water is permitted to penetrate into all parts thereof more freely than would be the case in a single chamber. After the clothes have been washed and rinsed as above described, the water may be entirely withdrawn from the casing 1 and the container rotated at a higher speed than that employed in the previous operations for the purpose

of extracting the water from the clothes. In using the device for the purpose of extracting water from the clothes the various advantages previously mentioned are of equal or even greater importance than in the washing. The separation of the clothes into several compartments results in the bulk of the clothes in each compartment being considerably smaller than would be in the case with a single large compartment, the water therein is more fully removed and the smaller bulk of clothes renders them less liable to injury. Moreover, the provision of chambers of cylindrical form avoids contact by the clothes with sharp edges in the interior of the chambers and also prevents the mass of clothes from becoming wedged in any restricted or angular space therein. By closely fitting the cylinders and bearing blocks together and providing suitable packing material between these parts access of water to the space between the several cylinders is prevented and thus the danger of rusting of these parts largely prevented as well as the difficulty of operation by reason of the presence of water therein avoided.

What I claim is:—

1. A washing machine comprising a tub adapted to contain water, a clothes container rotatably supported in said tub and comprising a plurality of spaced cylindrical chambers fixedly secured together and arranged in parallel relation, and a hinged cover for one end of said cylindrical chambers whereby access may be had thereto for removing or replacing clothes therein, and means for rotating said container in said tub.

2. A washing machine comprising a tub adapted to contain water and provided at one end thereof with doors whereby access may be had to the interior thereof, a clothes container rotatably supported in said tub and comprising a plurality of spaced cylinders fixedly secured thereto and arranged in parallel relation and each provided with a plurality of openings for permitting the flow of water therethrough, a hinged cover for one end of said cylinders located adjacent to the said doors, and means for rotating said container in said tub.

3. In a device of the character described, a clothes container comprising a plurality of cylinders fixedly secured together and arranged in parallel relation and each provided with a plurality of openings for permitting the flow of water therethrough, means for firmly securing the several cylinders together, oppositely positioned hinged covers located at one end of said container permitting access to the interior of said cylinders, and means located between said cylinders for rotatably supporting the container.

4. In the device of the character described, a clothes container comprising a plurality

of cylinders arranged in parallel relation and fixedly secured together to prevent passage of water between contacting sides thereof, each of said cylinders being provided with a plurality of openings in the side wall thereof for permitting the flow of water therethrough, means located at opposite ends of said container and between said cylinders for excluding water from the space between said cylinders, said last named means serving as bearings for rotatably supporting said container, and hinged covers secured to one end of said container for permitting access to the interior of said cylinders.

15 5. In a device of the character described,

a clothes container comprising a plurality of cylinders arranged in parallel relation and fixedly secured together, each of said cylinders being provided with a plurality of openings in the side wall thereof for permitting the flow of water into and out of said cylinder, means between the contacting sides of said cylinders for preventing the passage of water therebetween, and means located at opposite ends of said container 20 and between said cylinders for excluding water from the space between said cylinders. 25

In testimony whereof I have affixed my signature.

GEORGE W. OLNEY.
